Primary Examiner — Jae Liang*Assistant Examiner* — Samantha Lynne Brodowski(74) Attorney, Agent, or Firm — CANTOR COLBURN LLP(57) CLAIM

The ornamental design for a handbag, as shown and described.

DESCRIPTION

FIG. 1 is a front view of a handbag, with a central strap in a draped position, extending over a top and front of the handbag;

FIG. 2 is a back view thereof, with the central strap extending into an interior of the handbag;

FIG. 3 is a bottom view thereof;

FIG. 4 is a side view thereof;

The hardware elements shown in FIGS. 2, 5, 6, and 7 which are bounded with broken lines form no part of the claimed design.
